CASTING MACHINE

Albert W. Morris, Springfield, Mass., assignor to
 Morris Engineering Corporation, a corporation
 of Rhode Island

Application April 12, 1935, Serial No. 15,938

6 Claims. (Cl. 22—92)

My present invention pertains to the art of casting, and has particular reference to an improved apparatus for facilitating and improving the casting of metal articles.

The casting of metal articles has heretofore been accomplished in sand molds and in metal molds. These molds have had disadvantageous features that have decreased production and increased cost; the sand molds must be carefully made up for each casting, and the metal molds have not been designed for facilitating inspection or for quickly ejecting the castings. It is the principal object of my invention to provide a metal mold construction which may be quickly and fully opened to permit inspection of the castings and the mold, and quick removal of the castings.

To this end, I have provided a molding apparatus which utilizes a hinged mold adapted to open flat, and to close so as to aid and assist pouring of the casting metal. The quick opening and the accessibility of the mold parts permit use of inserts of different materials, and drawing or bleeding of the castings to provide hollow castings without use of cores.

With the above and other objects and advantageous features in view, my invention consists of a novel arrangement of parts more fully disclosed in the detailed description following, in conjunction with the accompanying drawings, and more specifically defined in the claims appended hereto.

In the drawings,

Fig. 1 is a front elevation of the apparatus, parts being broken away, the mold sections being closed;

Fig. 2 is a side elevation thereof, parts being in section and other parts broken away;

Fig. 3 is a top plan view thereof, and

Fig. 4 is a top plan view with the mold sections in opened position.

I have found it desirable to provide a simple, inexpensive mold for casting metals, the mold being permanent, and opening fully to permit inspection and removal of the castings, and closing so as to facilitate pouring. The use of permanent metal molds insures castings that are accurate in size, are smooth-surfaced, and require very little machining and finishing. Moreover, there is no sand in the mold or on the surface of the castings.

The preferred construction utilizes two hinged mold sections, which are pneumatically opened to a horizontal position, and swing to a closed position, an intermediate vertical cen-

tral section or "cheek" being used if desired. The mold sections are held in upright position when closed, and are preferably adapted for gravity filling through the top, although the closed sections may be in any desired position, and the inlet may be at the bottom or side; the mold is suitable for manual or for automatic pouring.

Referring to the drawings, the novel casting apparatus comprises a base plate 10, on which a support cylinder 11 is mounted, as by means of bolts 12. The interior of the cylinder is utilized as a piston chamber 13, in which a piston 14 is adapted to reciprocate, the piston having the usual packing and having a central bore to receive a piston rod 15 extending upwardly therefrom for a purpose hereinafter explained.

The upper end of the cylinder 11 is closed by a plate 16, having a central bore 17 through which the piston rod passes, the plate having an externally threaded peripheral boss 18 concentric with the bore and receiving a rod packing 19 which is locked in place by a gland nut 20. The piston is moved by fluid pressure, preferably air under high pressure, admitted through inlet conduits 21 in the base plate and the upper plate, the lower conduit communicating with an inlet chamber 22 which communicates with the interior of the cylinder below the piston and accommodates the piston rod holding bolt 23 when the piston is in down position. The inlet conduits are threaded to receive fluid pressure fittings, and the fluid pressure supply and exhaust is controlled by hand valve or foot valve control means of standard type. The plate 16, see Fig. 3, is generally elliptical in form, and is provided with bores 24 at the ends which receive support rods 25, the lower ends of these rods being stepped, see Fig. 2, and set into recesses or bores 25a in the base plate 10. The support rods 25 have heads 26 secured to the upper ends thereof, in which spacing shafts 27 are mounted, see Figs. 1 and 2.

Referring now to Fig. 2, the piston rod 15 has a cross rod 28 mounted in the upper end thereof; a central cheek member 29 acts as a base for the outer mold sections and has a depending boss 30 locked to the piston rod and the cross rod, and end plate portions 31 which have parts 32, 33 extending above and below the cross rod. The parts 32 contact vertical guide channels 34 formed in the heads 26, which function to guide the upward movement of the central cheek member, and the parts 33 have limit stop rods 35 secured thereto, which pass through

suitable openings 36 in the upper closure plate 16 and have resilient washers 37 which contact the lower face of the plate 16 to limit opening movement of the mold parts.

5 Two hinged mold sections 38, 39 are utilized, having hinge rings 40, 41 which embrace the cross rod 28, and cam strips 42, 43 which slidely engage cam cylinders 44, 45 of the heads 26. Spring arms 46, 47 are secured to the mold sections and extend around the associated spacing shafts 27. Each mold section has one or more mold recesses 48, with inlets 49 and bottom connections 50.

The operation of the improved casting apparatus may now be explained: With the mold sections in the position shown in Fig. 1, fluid material, such as molten metal, is poured into the inlets, to completely fill the mold recesses and the bottom connections. The molten metal quickly 15 chills, and compressed air is admitted to force the piston upwardly, thus causing a simultaneous upward movement of the cheek section and a swinging movement of each mold section, until the mold sections are horizontal, as indicated in 20 Fig. 4. These movements break the castings from the mold recesses and permit quick removal; the mold recesses may then be examined, and cleaned if necessary, and the air pressure reversed to pull the cross rod and the associated mold sections and cheek section, downwardly to again close.

It is thus clear that the improved mold includes separable mold sections, which are opened horizontally to facilitate removal of the castings, 35 and to permit inspection, the parts closing tightly under resilient pressure to receive the poured metal. This construction of mold is particularly suitable for simple castings such as electric irons, clutch plates, fly wheels, gear wheels, and the like, these castings being quickly and economically made. The flat mold sections are readily manufactured, and may have liners if desired, which are most suitable for the material being cast; moreover, the pouring may be from below, 40 under pressure. The resulting castings are uniform, accurate in size, and smooth surfaced, thus requiring a minimum of machining and finishing.

While I have described a specific constructional embodiment of my invention designed for metal castings, the structure of the mold is suitable for casting other materials, such as cements, plaster of Paris, glass, or other fluid material; changes in the size and shape of the parts, and in the materials thereof, may be made to suit the requirements for different molding duties, within the spirit and the scope of the invention as defined in the appended claims.

I claim:

1. In a casting machine, a frame, three mold sections movably mounted in said frame and including a central cheek member slidably mounted in said frame and having a pivot, the outer mold

sections having mold recesses and being hinged to said pivot on the cheek member, means positioned on said frame for moving said pivot, and guide members on the frame and cooperating arms on the outer mold sections for positioning said outer mold sections at a predetermined angle to the cheek member. 5

2. In a casting machine, a frame, three mold sections movably mounted in said frame and including a central cheek member slidably mounted in said frame and having a pivot, the outer mold sections having mold recesses and being hinged to said pivot on the cheek member, means positioned on said frame for moving said pivot, and guide members on the frame and cooperating 10 cam elements on the outer mold sections for positioning said outer mold sections in contacting engagement with the cheek member. 15

3. In a casting machine, a frame, three mold sections movably mounted in said frame and including a central cheek member slidably mounted in said frame and having a pivot, the outer mold sections having mold recesses and being hinged to said pivot on the cheek member, means positioned on said frame for moving said pivot, guide members on the frame, cooperating arms on the outer mold sections for positioning said outer mold sections at a predetermined angle to the cheek member, and cam elements on the outer mold sections for positioning said outer mold sections in contacting engagement with the cheek member. 20 25

4. In a casting machine, a frame, a mold base mounted to slide therein, and a mold section movably mounted thereon, said mold section having a mold recess and being hinged to a pivot on the base, means for sliding said base to move said pivot, and guide means on the frame and cooperating arm means on the mold section for positioning said mold section at a predetermined angle to the base. 30 40

5. In a casting machine, a frame, a mold base mounted to slide therein, and a mold section movably mounted thereon, said mold section having a mold recess and being hinged to a pivot on the base, means for sliding said base to move said pivot, and guide means on the frame and cooperating cam means on the mold section for positioning said mold section in contacting engagement with the base. 45

6. In a casting machine, a frame, a mold base mounted to slide therein, and a mold section movably mounted thereon, said mold section having a mold recess and being hinged to a pivot on the base, means for sliding said base to move said pivot, guide means on the frame, cooperating arm means on the mold section for positioning said mold section at a predetermined angle to the base, and cooperating cam means on the mold section for positioning said mold section in contacting engagement with the base. 50 55 60

ALBERT W. MORRIS.
